UNITED STATES PATENT OFFICE.

DAVID S. CARTER, OF DETROIT, MICHIGAN, ASSIGNOR TO LARNED, CARTER & COMPANY, OF DETROIT, MICHIGAN, A CORPORATION OF MICHIGAN.

OVERALL-POCKET.

1,299,552.

Specification of Letters Patent.

Patented Apr. 8, 1919.

Application filed March 16, 1917. Serial No. 155,175.

To all whom it may concern:

Be it known that I, DAVID S. CARTER, a citizen of the United States of America, residing at Detroit, in the county of Wayne and State 5 of Michigan, have invented certain new and useful Improvements in Overall-Pockets, of which the following is a specification, reference being had therein to the accompanying drawings.

10 This invention relates to pockets for overalls or the like and refers more particularly to a pocket to receive a rule or other tool or tools.

15 Among the objects of the invention are to provide a pocket of the character above referred to which will receive a rule or rules or other articles of different length and will prevent the accidental displacement of the article from the pocket; to so construct and 20 arrange the pocket that free access can be had to the articles within the pockets for withdrawing the same; to provide a construction in which the rear side of the pocket is inclined so as to automatically guide the 25 article into a position where it will be locked from displacement when inserted in the pocket; and in general to provide a new and improved pocket construction.

30 The invention also resides in such other details of construction as will more fully hereinafter appear.

In the drawings:

Figure 1 is a plan view of a pocket embodying my invention;

35 Fig. 2 is a similar view showing an article being inserted in the pocket;

Fig. 3 is a cross sectional view on the line x—x of Fig. 1.

40 In overalls or other garments pockets are often provided for receiving a measuring rule or other article. When the person wearing the garment bends over or assumes positions other than an upright position, the rule or other article is often lost from the pocket, 45 and the present invention particularly contemplates a simple and efficient arrangement whereby the rule or other article will be locked from accidental displacement without interfering with convenient access of the 50 article to be used.

In the particular construction shown in the drawings, A designates the overall to

which the pocket B is attached, this pocket being sewed to the garment by stitching C, C', C² and C³, the latter seam, however, extending but a portion of the way of the side D and being preferably formed integral with the side seam E which connects the front and rear sections E' and E² of the overalls. From the upper end of the seam C the edge 60 G of the pocket is not connected to the garment, thus leaving an opening H through which the rule or other article can be inserted in the manner shown in Fig. 2.

65 It will be noticed that the seam C is inclined upwardly toward the opening H, while the seam C' tapers from the top to the bottom toward the seam C², thus giving an inclined side J to the pocket. This inclined arrangement of the side of the pocket opposite the opening through which the article is inserted, provides a material advantage, in that as the article such as the rule K is inserted in the pocket its lower edge K' will ride against the edge J and be forced toward 70 the seam C³. This will automatically throw the upper end K² of the article back away from the opening and beneath the locking edge formed by the seam C. The article will therefore be held from accidental displacement irrespective of its length, since the inclined wall J will guide it up against the locking seam, rather than toward the opening.

75 However the inclined relation of the edge G gives a relatively wide opening through 80 which access can be had to the tool or other article for removing the same from the pocket. The invention in its broader aspects is not limited to the particular location of the pocket and various other changes in the 85 details of construction can be made within the scope of my invention.

90 What I claim as my invention is:

95 1. In a garment, a pocket comprising a pocket member having a rear edge inclined from the vertical line, a front edge arranged in substantially a vertical line, and a completely closed top portion extending but a portion of the way from the rear edge to the plane of the front edge, said closed top portion being arranged at substantially right angles to said rear edge, there being an opening portion positioned between the front end 100 of the upper edge and the upper end of the

front edge and diagonally inclined throughout its extent.

2. In a garment, the combination with two sections united by a substantially vertical seam, of a pocket having one edge stitched into said seam, an opening portion inclining upward from the stitched edge away from

said seam, and the remainder of the periphery of the pocket being stitched throughout its extent to one of said sections including a rear edge inclined relatively to said seam.

In testimony whereof I affix my signature.

DAVID S. CARTER.
